UNITED STATES PATENT OFFICE.

STUART E. NORTON AND JOSEPH P. SHEVLIN, OF DENVER, COLORADO.

DESIGN FOR A PERFUME ATOMIZER.

Application filed March 8, 1929. Serial No. 30,392. Term of patent 7 years.

To all whom it may concern:

Be it known that we, STUART E. NORTON and JOSEPH P. SHEVLIN, both citizens of the United States, residing at Denver, in the county of Denver and State of Colorado, have invented a new, original, and ornamental Design for Perfume Atomizers, of which the following is a specification, reference being had to the accompanying drawing, forming a part hereof.

In the drawing Fig. 1 is a side elevation of the perfume atomizer, showing our new design. Fig. 2 is a plan view thereof.

We claim:

The ornamental design for a perfume atomizer as shown.

STUART E. NORTON.
JOSEPH P. SHEVLIN.
